2 Claims. (Cl. 233—20)

The present invention relates to sludge centrifuges of the intermittently discharging type in which a first valve, hydraulically actuated in the axial direction of the rotor shaft, opens and closes sludge discharge openings located in the rotor wall and in which a second axially movable valve, when hydraulically actuated, opens discharge outlets for the operating liquid which actuates the first valve.

A sludge centrifuge of this type is disclosed, for example, in Swedish Patent No. 178,744. In such a centrifuge, the operating liquids which actuate both valves have a common outlet. The second valve is opened and maintained open by the pressure exerted by a liquid ring on one side of the valve against the action of springs, and the latter cannot close the valve before the pressure exerted by the liquid ring has dropped below a certain value. Thus, the time during which the first valve maintains the sludge discharge opening open will depend upon the time which elapses before the liquid pressure on one side of the second valve drops below this certain value. In some cases, however, it is desirable to reduce considerably the time during which the sludge discharge openings are kept open, particularly when it is required to discharge only comparatively small sludge quantities and only as little as possible of the liquid to be separated.

According to the present invention, this time reduction is obtained by an arrangement in which the operating liquid for the first valve is discharged therefrom through openings leading outside the rotor entirely apart from the chambers to which the operating liquid for opening the second valve is supplied. If the closing force is sufficiently high, the second valve can close as soon as the latter chamber has been entirely or partially emptied of operating liquid, in spite of the continued outflow of operating liquid from the discharge openings of the first valve.

The closing of the second valve can, like its opening, be effected by hydraulic action which is brought about by means of an operating liquid normally constituted by fresh water. However, in some instances, as on ships where the consumption of fresh water must be economized, springs are advantageously used for closing the second valve.

According to another time-shortening measure, the discharge openings for the operating liquid for the second valve open directly into atmosphere outside the rotor, so that no liquid cushions which could counteract the closing of the second valve are formed at these discharge openings.

The invention is described more in detail below, reference being made to the attached drawing in which the single illustration is a vertical sectional view of part of a preferred form of the new centrifuge having a vertical axis of rotation.

In the drawings, reference numeral 1 designates the rotor body having a cover 2 and a locking ring 3 which secures the cover to the rotor body. Relatively large sludge discharge openings 4 are located in evenly spaced relationship along the periphery of rotor body 1. While the separation is in progress, these openings are kept closed by means of a conical valve disk 5 having an annular ridge 6 which makes sealing contact against the

2

cover 2. Reference numeral 7 designates a conventional set of conical disks in separating space 9 of the rotor. The liquid to be separated is led into the separation chamber 9 by way of a so-called distributor 8. The

5 rotor is carried and driven by a vertical shaft 10. A liquid in the interspace 11 between the valve disk 5 and the bottom of the rotor body 1 generates, under the action of the centrifugal force, the axial power or upward thrust required for closing the valve disk. Channels 12 distributed along the rotor periphery are provided for the discharge of operating liquid from the chamber 11. These channels or discharge openings are closed by a ring-shaped valve 13 provided with a number of pads 14 (such as nylon) corresponding to the number of 15 the channels 12, each pad sealing a channel outlet. A plate 15, which supports peripherally-spaced compression springs 16, is fixed to the bottom of the rotor body 1. These springs urge the valve 13 upward into closing position.

20 The shaft 10 is surrounded by a stationary cylindrical body 17 provided with a vertical channel 18 to which is connected a supply pipe 19 for an operating liquid, such as water. The plate 15 is provided with a ring-shaped chamber 20 into which the channel 18 opens and from which a channel 21 leads to the chamber 11. The chamber 20 is provided at the bottom with drainage holes 22 and communicates at the top, by way of an overflow outlet 23 and a channel 24, with a ring-shaped interspace 25 between the ring-shaped valve 13 and the bottom of 30 the rotor body 1. The ring-shaped valve 13 slides in liquid-tight relation against a cylindrical surface 26 on the bottom of the rotor body 1. The chamber 25 is further provided with drainage holes 27 arranged in the ring-shaped valve 13.

35 It will be understood that the rotor 1 is provided at its upper portion with the usual outlet (not shown) for the liquid separated as the lighter component in separating chamber 9, the separated liquid being displaced inwardly from the spaces between discs 7.

In the operation of the centrifuge, let it be assumed that rotor 1 is being driven and that the centrifuging operation is in progress with valve disk 5 in its closed position. Water is supplied through the pipe 19 at such a low rate that the chamber 11 is kept filled only to the 40 level determined by the holes 22 through which all the surplus water is ejected. When sludge is to be discharged from the centrifuge, the rate of supply of water through the pipe 19 is increased so that the liquid level in the chamber 20, in spite of the outflow through holes 22, is 45 displaced radially inward whereby water flows over the overflow outlet 23 and through the channel 24 into the chamber 25. When the liquid level in chamber 25 has increased sufficiently inward, despite the outflow through the drainage holes 27, the liquid pressure in the chamber 25 (together with the liquid pressure against the pads 14) overcomes the closing power of the springs 16 so that the valve 13 opens the channels 12. Water is then 50 discharged from the chamber 11 through these channels, whereupon the valve disk 5 opens after the liquid level in chamber 11 has been displaced a certain distance outward. Sludge is then discharged through the openings 4. The supply of water through the pipe 19 is interrupted 55 after a certain period of time corresponding to the time during which it is desired that the openings 4 are maintained open. The chamber 25 is thus drained through the openings 27 and, at the same time, water continues to flow out through the channels 12. After the liquid level has decreased sufficiently in the chamber 25 (or this chamber has been completely drained) the springs 60 16 overcome the opposing force on the ring-shaped valve 13 and thus close this valve before all the water in the 65 70

chamber 11 has been discharged through the channels 12. The water remaining in the chamber 11 is then capable of closing the valve disk 5 before all the contents of the separation chamber 9 has been ejected through the openings 4. Water is then supplied again through the pipe 19 in such quantity that the chamber 11 is filled to the level of the holes 22, so that the valve disk 5 is kept securely closed against the increasing downward force exerted on it as the separation chamber 9 is re-filled with feed material from distributor 8.

It will be apparent that the parts 17 through 24 form in effect a liquid supply means for feeding an operating liquid to the first chamber 11, such means being operable also to feed operating liquid to the second chamber 25.

I claim:

1. A sludge centrifuge comprising a centrifugal rotor mounted for rotation about an axis and having a separating space and also having a peripheral opening for discharging separated sludge from said space, a first valve in the rotor partly defining said separating space and movable axially of the rotor to open and close said sludge discharge opening, said valve forming with the rotor a first operating liquid chamber, the rotor having a first operating liquid outlet leading from the outer portion of said first chamber to the outside of the rotor,

a second valve carried by the rotor and normally biased to a closed position for closing said first outlet, the second valve forming with the rotor a second operating liquid chamber and being movable axially of the rotor by liquid in said second chamber to an open position for opening said first outlet, and liquid supply means communicating with said chambers for feeding operating liquid to said first chamber to move the first valve into position for closing the sludge discharge opening, said means being operable to feed operating liquid to said second chamber to move the second valve to its open position for discharging liquid from said first chamber, said second chamber having an operating liquid outlet separate from said first liquid outlet.

15 2. A sludge centrifuge according to claim 1, in which said liquid outlet from the second chamber opens directly into atmosphere outside the rotor.
